(57) CLAIM

The ornamental design for the hair braider kit, as shown and described.

DESCRIPTION

FIG. 1 is a perspective view of a hair braider kit showing our new design and including a hair braider with a stand and with a comb contained in a storage position;

FIG. 2 is a side elevational view of the hair braider kit taken from the right of FIG. 1;

FIG. 3 is a side elevational view of the hair braider kit taken from the left of FIG. 1;

FIG. 4 is front elevational view of the hair braider kit taken from the left front of the perspective view in FIG. 1;

FIG. 5 is a back elevational view of the hair braider kit taken from the right rear of the perspective view in FIG. 1;

FIG. 6 is a top plan view of the hair braider kit shown in FIG. 1; and,

FIG. 7 is a bottom plan view of the hair braider kit shown in FIG. 1.
